T. ABEL

FURNACE GRATE STRUCTURE

Filed Nov. 29, 1921

Theodore Abel Inventor

By Chas B. Billman Attorney

UNITED STATES PATENT OFFICE.

THEODORE ABEL, OF CLEVELAND, OHIO.

FURNACE-GRAVE STRUCTURE.

Application filed November 29, 1921. Serial No. 518,500.

To all whom it may concern

Be it known that I, THEODORE ABEL, a citizen of the United States, residing at Cleveland, in the county of Cuyahoga and 5 State of Ohio, have invented certain new and useful Improvements in Furnace-Grate Structures, of which the following is a specification.

My invention relates to improvements in 10 furnace grate structures, the improved grate relating to that class or type in which the grate proper is removably and rotatably mounted and is adapted to be given a horizontal shaking movement to discharge the 15 ashes and in which the combustion of the fuel is supported through an annular over-draft.

The primary object of the invention is to 20 provide a generally improved grate structure of the class indicated, which will be exceedingly simple in construction, cheap of manufacture, and efficient in use.

A further important object is to provide 25 an improved shaker grate having an annular air circulating grate portion and a central ash receiving receptacle over which the main body portion of the fuel is adapted to be initially placed and maintained so that combustion may be supported at all times over 30 and about the same through the annular draft or grate portions of the grate above referred to.

A still further object is the provision of an 35 improved shaker grate and grate mounting adapted to be readily inserted in or moved from the ash pit portion of any ordinary furnace through the usual door opening to the same.

A still further object is the provision of an 40 improved dumping closure bottom for the central ash receiving receptacle pivotally supported on a combined grate dumping and shaker handle extending forwardly to the door leading to the ash pit whereby, if desired, the ashes or clinkers arising from the combustion of fuel may be readily deposited within the ash pit and removed therefrom or the shaker grate be given a horizontal reciprocatory or shaking movement to discharge the ashes through the annular grate portion thereof for the establishment of more perfect combustion.

With the above mentioned and other ends 45 in view, the invention consists in the novel 50 construction, arrangement, and combination of parts, hereinafter described, illustrated in

one of its embodiments in the accompanying drawings, and particularly pointed out in the appended claims.

Referring to the drawings, forming a part 60 of this specification, Figure 1 is a top plan view, partly in horizontal section, of the ash pit and fire box portions of an ordinary furnace equipped with a grate structure constructed in accordance with this invention. 65

Fig. 2, a central vertical sectional view of the same, the central ash receiving well or receptacle being filled with ashes and covered with fuel to illustrate the combustion supporting draft over and in the same. 70

Similar numerals of reference designate like parts throughout all the figures of the drawings.

The improved grate structure is adapted 75 to be readily inserted in or removed from the ordinary ash pit portion of any ordinary furnace.

In the present instance I have shown my 80 improved grate structure removably mounted in an ash pit 1, embodying parallel extending side walls 1^a, extending from the door side 1^b, and terminating in a rounded portion 1^c. The casing forming the ash pit is surmounted by a round or circular shaped 85 fire box 2.

The above described furnace parts and 90 features of construction may be of any suitable and convenient form, and forming no part of this invention need not be described in detail.

Referring to the improved grate structure, 95 it will be seen that I provide an improved supporting member 3, adapted to be readily inserted in and removed from the upper portion of the ash pit portion of the furnace and being also adapted to removably receive and carry the shaker grate, proper, hereinafter referred to. The main supporting member 3, may be of any suitable and convenient form, and, in the present instance, 100 comprises side bars 3, terminating in a ring shaped grate receiving and supporting portion 3^a, said side bars 3 being provided at their front with a transverse supporting bar 3^b, terminating in supporting lugs 3^c. In 105 the present instance, the shaker grate support is provided with an intermediate bar 3^d, and it will thus be seen that the support as a whole is of open formation. As a means of inserting and removing the support, the 110 ring portion is provided with lugs 3^e, adapted to be initially inserted in bearing recesses

1^c, in the walls of the ash pit, and as a means of supporting the front ends of the support suitable lug bolts 1^e, may be inserted in suitable openings near the front ends of 5 the side walls 1^a, and connected by means of nuts 1^f, adapted to engage beneath the lugs 3^c of the supporting frame.

The shaker grate receiving and supporting portion 3^a, is provided with spaced off-set 10 flanges 3^f, the latter being adapted to receive and slidably support the marginal edges of the shaker grate to be now described.

The improved shaker grate comprises inner and outer rings 4 and 4^a, respectively, 15 connected by spaced radially extending grate bars 4^b, forming a series of draft openings 4^c, and which draft bars and openings as a whole form an annular combustion supporting draft passage, the inner ring 4 being imperforate throughout and being in 20 the form of a cylindrical wall extended downwardly forming a depending ash receiving vessel or well, as shown most clearly in Fig. 2 of the drawings.

25 The receptacle or well is provided at its base with a closure bottom 4^d, adapted to receive and normally support the ashes, clinkers and other products of combustion, the bottom 4^d being also of imperforate formation and the central portion of the fuel 30 upon the grate and within the fire pot being adapted to be supported immediately above the receptacle forming walls 4.

As a means of removably supporting the 35 closure bottom 4^d within the receptacle 4, and particularly as a means of operating such closure bottom and horizontally reciprocating the shaker grate as desired, bearing openings are formed within the lower portions 40 of the walls of the receptacle, and the closure bottom 4^d, is provided with a bearing lug 4^e, to removably receive and contain a bar or shaft 5, which forms a pivot support for the closure bottom and extends forwardly beneath the shaker grate and grate 45 supporting member to the door side of the ash pit where such combined grate dumping and shaker handle may be operated to either dump the ashes and clinkers, or to shake the 50 grate as desired. A set screw 5^a, is adapted to secure the closure bottom upon the bar 5 in the tilting or dumping movement of the bottom and a lug 4^f, at one side of the receptacle is adapted to normally hold said bottom 4^d in its closed or normal position.

When the receptacle or well 4 is filled with 55 ashes or other products of combustion and a supply of fuel is placed over the central portion of the grate and ignited, it should 60 be understood that the air or draft passing through the annular draft or grate portion

of the grate in passing upwardly over and through the fuel will create a draft over the central ash receiving receptacle and within and over the supported fuel substantially as 65 indicated by the arrows in Fig. 2 of the drawings.

From the foregoing description, taken in connection with the accompanying drawings, the operation and advantages of my 70 invention will be readily understood.

Having thus described one of the embodiments of my invention, without having attempted to set forth all the forms in which it may be made, or all the modes of its use, 75 what I claim and desire to secure by Letters Patent, is,—

1. In a furnace grate structure, a shaker grate comprising an annular grate portion and a normally closed ash receiving receptacle.

2. A grate structure, comprising a supporting member, including a ring shaped opening and a surrounding ring having spaced supporting flanges, a shaker grate removably mounted therein and supported on said flanges, said grate being provided with an annular horizontal grating and a central depending ash receiving receptacle including an imperforate cylindrical side wall, a closure bottom in said receptacle, and a bar extending through said receptacle forming a pivot support for said bottom and projecting forwardly beneath said shaker grate whereby the latter may be rotatably reciprocated or said bottom tilted to dump the contents of said receptacle.

3. A grate structure, comprising a removable supporting horizontally connected member of open formation including a shaker grate receiving opening and spaced grate supporting flanges, means for removably supporting said supporting member opposite said hinged connection, a shaker grate removably mounted in said opening and supported on said spaced flanges, said shaker grate being provided with an annular grating and a central depending ash receiving receptacle, a closure bottom of imperforate formation for said receptacle, and a bar extending from said receptacle forming a pivot support for said bottom and extending forwardly beneath said shaker grate whereby the latter may be reciprocated or said bottom tilted to dump the contents of said receptacle, and said hingedly connected member being inserted or removed or lowered or elevated at the front relative to said hinged connection.

In testimony whereof I have affixed my 120 signature.

THEODORE ABEL.
